VERTICAL COKING RETORT BENCH

Gottfried Goetz, Webster Groves, Mo., assignor
to Ludwig Kern, Webster Groves, Mo.

Application July 21, 1932, Serial No. 623,701

1 Claim. (Cl. 202—125)

This invention relates to vertical coking retort benches, and with regard to certain more specific features, to retorts for distilling or coking carbonaceous materials such as coal, in shapeless or 5 lump coke form.

Among the several objects of the invention may be noted the provision of a retort bench of the class described which includes means adapted for more advantageously removing the products of 10 distillation without destroying the same; a retort bench including improved means for charging and delivering the coked product; a retort bench having improved heating means; a retort bench embodying improved means for recovering and 15 conserving heat; a retort bench including improved means for quenching the product as it is delivered; and a retort bench of the class described which is relatively simple in construction and operation. Other objects may be in part ob- 20 vious and in part pointed out hereinafter.

The invention accordingly comprises the elements and combinations of elements, features of construction, and arrangements of parts which will be exemplified in the structures hereinafter 25 described, and the scope of the application of which will be indicated in the following claim.

In the accompanying drawings, in which is illustrated one of various possible embodiments of the invention,

Fig. 1 is a vertical longitudinal section of a 30 retort bench employing the present invention; and,

Fig. 2 is a vertical cross section of the retort 35 bench shown in Fig. 1.

Similar reference characters indicate corresponding parts throughout the several views of the drawings.

Referring now more particularly to Fig. 1, numeral 1 indicates a general supporting structure 40 for a retort bench comprising individual retorts 3 arranged as a battery. In the drawings, it will be noted that six separate retorts 3 are provided. The number six is not, of course, to be considered as limiting the invention; it is apparent that the 45 battery or bench may comprise any number of retorts desired. The retorts 3 are arranged in groups of three, each group of three discharging into a common quenching chamber 5. Each quenching chamber 5 in turn delivers from the 50 three retorts to a discharge conveyor 7, which may be of any suitable design.

The separate retorts 3 are each quite narrow 55 relative to their height, and taper upwardly so that the lower end thereof is of greater area than the upper end. The retorts are made narrow in

order that the heat transfer to the coal or the like included therein may be effected more rapidly, as, it will be understood, coal is a relatively poor conductor of heat and, if it is attempted to heat a relatively thick body of coal from the outside, the time lag before the center of the body is brought to the desired temperature is distinctly objectionable. The taper of the retort aids in discharging the same.

The upper end of each retort 3 is provided with a closure means 9, which may be of any suitable construction, such as that shown in my copending patent application, Serial No. 623,702, filed July 21, 1932. The lower end of each retort 3 is likewise closed by a discharge door 11, which may likewise be of any suitable construction, such as that shown in my copending patent application, Serial No. 623,703, filed July 21, 1932.

Referring to Fig. 2, it will be seen that each of the retorts 3 is relatively long from front to back, as is customary in this art. In the present invention, a central partition 13 divides each retort 3 into a front section 3A and a back section 3B. The purpose of this lateral division will appear hereinafter.

Each end wall 15 of each retort 3 is provided with a series of openings 17 discharging into a vertical vapor outlet header 19. The openings 17 extend, or are distributed, from the top to the bottom of the retort 3. These outlets 17 comprise a particular advantage of the present invention. In prior retorts, it has been customary to withdraw the products of distillation, or vapors, or tars, from a single point or points all near the top of the retort. This meant that distillation products coming from the coal near the bottom of the retort were obliged to pass through a mass of highly heated coal of considerable length, and frequently to come into contact with the even more highly heated walls of the retort, with the result that the tars and similar products were cracked, or subjected to pyrogenic or secondary decomposition, by the heat, and the character of the distillation products, especially the primary tars, was thereby undesirably changed. In the present invention, outlets are provided for the distillation products substantially at all levels of the retort, and thus the vapors are drawn off without being required to pass through a large body of overheated coal or to come in contact with objectionably large areas of overheated walls.

As a result of this provision, the products of distillation obtained through utilization of the present invention are considerably enhanced in 55

value over similar products obtained from prior retorts.

Further vapor outlets 21 are provided along the top upper edges of the retorts 3, on each side.

5 The outlets 21 each discharge into a main vapor header 23, into which the vertical vapor headers 19 also discharge. The header 23 conducts the vapors to suitable condensate recovery apparatus and the like, which is customary in the 10 art of coal carbonization.

Not only the end walls 15 of the retorts 3, but also both sides of the central partition 13, are provided with the outlets 17. Thus additional provision is made for the withdrawal of the 15 vapors produced substantially as quickly as they are formed. This constitutes the primary advantage of the partition 13. It will be understood, however, that the partition 13 may be dispensed with, if the retort is short enough, or 20 that it may be repeated whereby the retort is divided into three or more sections, if said retort is sufficiently long to warrant such construction.

It will be noted that each outlet 17 slopes upwardly from the point that it leaves the retort 3. This upward slope is advantageous, as it prevents lodging of lumps of coal in the outlet channels in such manner as to obstruct the drawing of vapors therethrough, to any objectionable extent.

25 30 As has heretofore been indicated, each set of three retorts 3 discharges into a common quenching chamber 5. This arrangement is particularly advantageous when the customary order of charging, heating, and discharging retorts is followed in operation. The provision of a common quenching chamber is also highly advantageous in that it is conserving of heat, as will hereinafter be pointed out, and in that it permits the accumulation of coke at the retort until such 35 time as it is sufficient in amount to fill a car or the like. A further advantage of this construction is that, with the provision of the quenching chamber in direct association with the retorts, the coke is delivered substantially cold, 40 and does not require quenching means exterior to the retort battery.

45 Referring to Fig. 1, it will be noted that each quenching chamber 5 is funnel-shaped, that is, it is provided with sloping bottoms 25, the angle 50 of which is suited to the angle of slip of the coke to be made. In each chamber 5 are provided a series of breaker bars 27 which extend across the chamber 5 laterally, and are secured in the sides thereof. Vertical bars 29 strengthen and support the bars 27. The bars 27 serve to break the coke, as it is delivered from the retorts, into 55 relatively large lumps, which, however, are sufficiently smaller than the lumps delivered directly from the retorts to permit of their falling 60 to the bottom of the quenching chamber. That is, each retort 3, when it is discharged, discharges its contents substantially in a single block, which is of quite considerable size. The breaker bars 27 serve the useful purpose of breaking these 65 retort-size lumps, as they fall under the influence of gravity toward the bottom of the chamber 5, into lumps of such size that they are easily deliverable to the discharging mouth of the quenching chamber.

70 75 Mounted in sideward recesses in the walls of the chamber 5 are a series of pipes 31, which carry the quenching medium for the coke. Water, for example, may be used as a quenching medium; steam may likewise be used for quenching under certain circumstances. The pipes 31 are pro-

vided with spaced openings directing the water or the like against the accumulated mass of coke in the bottom of the chamber 5. In this way, the coke is quenched substantially as it leaves the retort 3 and before it is delivered from the retort battery. The pipes 31 are desirably mounted in the recesses, as shown, so that they do not present obstructions to the movement of the coke.

The sloping walls 25 of the chamber 5 terminate in a discharge spout 33, which may be closed by suitable closure means to permit the accumulation of the desired quantity of coke. Included in the discharge mouth 33 is a rotary coke-breaker 35, which is advantageously of the 15 type shown in my copending patent application, Serial No. 623,705, filed July 21, 1932. The breaker 35, when it is not rotating, constitutes the closure means above referred to, as the lumps of coke are too large to pass the same. The rotary breaker 35 reduces the rather large lumps, formed by the breaker bars 27, into suitably sized small lumps, which may be used directly for metallurgical or household consumption or like purposes.

20 25 It is thus seen that, in the normal course of events, quenched, broken, small lump coke is delivered on to the discharge conveyor 7, whence it may be transported to any suitable destination.

30 35 The heating system of the retorts is substantially as follows:

Along the side of each retort 3 (see Fig. 2) are provided two series of horizontal flues 37, one series, 37A, corresponding to the front section 35 3A of the retort, and the other series, 37B, corresponding to the back section 3B of the retort. Each series of flues is joined, at the alternate ends 38 of the individual flues, to comprise a sequential arrangement from top to bottom, or from 40 bottom to top, as the case may be. The two series 37A and 37B are connected in series by the single top flue 37. (The letters "A" and "B" are hereinafter suffixed to each index number, to indicate the respective section referred to, and when 45 no letter is suffixed, the section is not in question.) The lowermost flue 37 on each series is connected, by a vertical flue 39, to a cross flue 41, which is in turn connected by vertical flues 43 directly to a regenerator 45. Communicating with 50 the cross flue 41 are a number of inlets 47 which in turn communicate with the quenching chamber 5. The inlets 47 are provided with suitable dampers as illustrated, so that the quenching chambers 5 may be placed in or out of communication with the flues 39 or 41.

55 The bottom of each regenerator 45 is connected by a short flue 49, controlled by a damper 51, to a tunnel 53, which leads to both a suitable stack and a suitable air inlet.

60 The flues 37 are each provided, at their ends corresponding to the end walls 15 of the retorts, with a burner 55 or 57. The burners 55 and 57 are identical, but are used in different manners as will be apparent hereinafter. The burners 55 and 57 are of a suitable gas-burning type, or the like, customary in the art.

65 Considering, for the present, that the heating gases travel in the direction indicated by the arrows in Fig. 2, the following is their course: Cold 70 air enters through the tunnel 53B and flue 49B to the regenerator 45B which, let it be assumed, has previously been heated in the manner to be described. The hot air now travels through the flues 43B to the horizontal flue 41B, and thence 75

through the vertical flue 39B to the heating flues 37B. The burners 55B are now ignited. It will be seen that the burners 55B propagate their flames in the direction indicated by the arrows, the rate of fuel and air feed being desirably such that the length of the flame is great enough to extend across through one flue 37B and back through the next higher flue 37B as the heating gases progress upwardly. The series of burners 57B is preferably turned off at this time, as their tendency would be to propagate a flame into a direction reverse to that desired under the present circumstances. Thus, considering that the direction of flow is that indicated by the arrows, it will be seen that each time the gases pass through a flue from the right to the left of Fig. 2 (right-hand section 3B of the retorts), they are supplied with additional heat from a burner 55B. The upward progress of the heating gases continues until the top flue 37 is reached. Thereupon the gases pass entirely across the top of the retort into the front, or left-hand section 3A thereof. That is, the top flue 37 extends past the central partition 13. The gases now commence a journey downwardly through the flues 37A corresponding to the front section 3A of the retort 3. The burners 55A are ignited, and propagate their flames into the direction of travel of the gases. After the gases have passed through the lowermost flue 37A, they are delivered into the vertical flue 39A, and thence through the flues 41A and 43A into the regenerator 45A. There the waste heat in the gases is absorbed by heating the regenerator 45A, to be recovered as hereinafter described. From the regenerator 45A the gases pass through flue 49A to the tunnel 53A and thence to the stack where they are discharged.

After operation has been continued in the manner indicated for a sufficient length of time adequate to heat the regenerator 45A, or to cool the regenerator 45B, the dampers are suitably changed in position so that the entire direction of flow of the gases is reversed. That is, instead of the cold air entering at tunnel 53B, cold air is now introduced through tunnel 53A and through the now preheated regenerator 45A. The travel of gases is now directly opposite to that indicated by the arrows in Fig. 2. The burners 55A and 55B have in the meanwhile been turned off, and the burners 57A and 57B all ignited. It will be seen that the burners 57 project a flame in the present direction of travel of the gases, as contrasted to the direction of flame produced by the burners 55 in the preceding stage of operation. The hot gases eventually pass through the right-hand regenerator 45B and reheat the same. When the right-hand regenerator 45B has been sufficiently heated, operation is again reversed to that originally described, and as represented by the arrows in Fig. 2.

Referring again to Fig. 1, it will be seen that the vertical flues 39 are in fact multiple, and so arranged as to provide for the series of heating flues 37 between the successive retorts in the bench, as well as those at the ends of the groups of three retorts. Suitable dampers are provided so that the retorts 3 may be heated one at a time or in groups, as desired.

It will be appreciated that upon quenching the hot coke in the chamber 5 in the manner described, large quantities of hot gases will be produced, the gases comprising, for example, steam and producer gas when water is used for quenching. In order to conserve heat, these gases are

desirably conducted through the inlets 47 to the horizontal flue 41, and conducted through the heating system together with the hot air from the regenerators. Or, in other instances, the hot gases from the quenching chamber 5 may be conducted through the inlets 47 and directly to the regenerators 45, in such manner as to aid in heating the regenerators without passing the steam throughout the whole heating flue system. Whether the gases from the quenching chamber 5 go directly to the regenerators 45 or to the heating flues 37 depends upon the direction in which the heating gases are travelling at the time.

The tunnels 53, it will be understood, desirably are constructed to supply all of the regenerators 45 in the given bench of retorts.

From the foregoing, it will be seen that a highly efficient, heat-conserving means is provided whereby the retorts as a whole are heated. Waste heat is greatly minimized, if not entirely eliminated.

The heating system, in general, it will be seen, comprises a reversible zig-zag style of horizontal flues, fed with hot air from a regenerative system, and supplied with flames at the ends of the flues in such manner that the flames are always travelling in the direction of the flow of heating gas, and delivering at their exit end into the regenerative system for absorbing the heat not utilized directly in heating the retort walls.

In the case that it is not desired to utilize the hot gases proceeding from the quenching operation in connection with the retort heating system, outlet pipes 61 are provided in each chamber 5 (see Fig. 2). Such pipes 61 are used when it is desirable to recover whatever volatile material, or combustible gases, that are produced during the quenching operation, or to recover directly the water gas produced by quenching with water or steam. It will be understood, of course, that when the pipes 61 are open, the inlets 47 are closed, or vice versa.

Under certain instances, it is desirable to introduce steam into the body of coal in a retort during the coking procedure. This is accomplished, in the present invention, by the provision of vertical steam headers 63 (see Fig. 2) at each end of the retort 3, the headers 63 being provided with a number of steam inlets 65 directed into the interior of the retorts 3.

The discharge conveyor 7 operates in a tunnel 67 extending transversely of the retort bench, and discharges at one end into a hopper 69 for delivery to any suitable car or the like. The end of tunnel 67 is preferably provided with an air-tight door 71, so that air is not admitted through said tunnel into the quenching chambers 5. This air-tight door 71 establishes a substantially sealed interior extending therefrom to the top of the respective retorts 3, through the discharge tunnel 67, quenching chamber 5, and respective retorts 3.

The present retort system is particularly designed for the coking of lump coal, in relatively shapeless form, to make the lump coke of commerce, as contrasted with shaped coal or coke forms, such as briquettes. In the case that the latter are to be made, it is more desirable to utilize the retort system shown in my copending patent application, Serial No. 623,700, filed July 21, 1932, which has many features in common with the present invention.

The present retort system is also particularly designed, and well adapted, for carrying out the coking processes disclosed in the copending patent applications as follows:

Ludwig Kern, Serial No. 342,315, filed February 23, 1929.

Ludwig Kern, et al., Serial No. 462,122, filed June 18, 1930.

5 Ludwig Kern, et al., Serial No. 462,126, filed June 18, 1930.

Ludwig Kern, et al., Serial No. 515,398, filed February 12, 1931.

In view of the above, it will be seen that the 10 several objects of the invention are achieved and other advantageous results attained.

As many changes could be made in carrying out the above constructions without departing from the scope of the invention, it is intended that all 15 matter contained in the above description or

shown in the accompanying drawings shall be interpreted as illustrative and not in a limiting sense.

I claim:

A vertical carbonizing retort having an oblong shape in horizontal cross section, including horizontal superposed heating flues arranged along the two wider sides thereof, and outlets from the retort for the products of distillation distributed vertically along the two narrower sides of the 10 retort, from top to bottom thereof, and a further series of outlets from the retort disposed horizontally along the tops of the wider sides of the retort, but above the topmost heating flue.

GOTTFRIED GOETZ. 15
